20 Claims. (Cl. 250—20)

1

The present invention relates to superregenerative wave-signal translating systems and is particularly directed to arrangements for improving the selectivity or frequency-response characteristic of such systems. While superregenerative arrangements of the type under consideration are subject to a variety of useful applications, they are especially suited for use as wave-signal receivers because of their inherent high sensitivity and, for convenience, the invention will be disclosed in that environment.

It is well understood that a superregenerative receiver comprises a regenerative oscillatory circuit and some form of quenching arrangement. The latter constitutes an integral part of the regenerative circuit in the case of receivers of the self-quenching type or constitutes a separate signal source coupled to the regenerative circuit in the case of separately quenched receivers. In either form, the quenching arrangement controls the conductance of the regenerative circuit, causing it to undergo repeating cycles in which the conductance has positive and negative values in alternate operating intervals. During any negative-conductance interval, the circuit exhibits an extraordinarily high gain and produces oscillations that are quenched or damped in the next succeeding interval of positive conductance. The oscillations which are thus periodically produced have a characteristic, such as an amplitude characteristic, which varies with the modulation of a received wave signal at the time the oscillations are initiated. These oscillations may thus be utilized in any of several well-recognized methods to derive the modulation components of the received signal.

The selectivity of the usual superregenerative receiver is analogous to that of several cascaded resonant circuits tuned to the oscillatory frequency of the regenerative circuit so long as the oscillations generated in any negative-conductance interval are quenched to an insignificant amplitude during the following positive-conductance period. For certain applications, it is highly desirable to provide for the receiver a substantially increased selectivity not realizable with the ordinary superregenerative receiver.

Some superregenerative receivers are known which have a selectivity sharper than usually encountered. For example, if the resonant-circuit damping during the positive-conductance intervals of a superregenerative receiver is insufficient to suppress the oscillations of any quench cycle adequately, the oscillations carry over from one quench cycle to the next and in-

fluence the response of the receiver to an applied wave signal in the following quench cycle. It may be shown that such a receiver has a serrated selectivity characteristic with peak responses occurring at the oscillatory frequency of the regenerative circuit and at frequencies spaced therefrom by integral multiples of the quench frequency. Although the carry-over phenomenon just described does increase the selectivity of the receiver, it is inflexible and is able to affect the selectivity characteristic only as a function of the quench frequency. Additionally, the modified selectivity can be attained only after several quench periods because the carry-over phenomenon inherently requires several quench cycles to manifest its effect.

Another prior receiver arrangement having somewhat improved selectivity is of the separately quenched type. It includes a quench-signal generator for applying to the regenerative circuit a quench signal of such wave shape that the conductance of the regenerative circuit is maintained in the vicinity of zero conductance from the outset of each oscillation build-up interval and for a substantial portion (approximately one-third) of each quench cycle. It is this relatively prolonged period of zero conductance which causes the superregenerative receiver to exhibit an increased selectivity. This method of selectivity control may be difficult to practice and is not as flexible as may be desired in certain applications.

It is an object of the present invention, therefore, to provide a superregenerative wave-signal translating system having a controllable selectivity characteristic and one which avoids one or more of the aforementioned limitations of prior arrangements.

It is another object of the invention to provide a superregenerative wave-signal translating system having an improved arrangement for controlling the selectivity characteristic of the system.

It is a further object of the invention to provide a superregenerative wave-signal translating system having a selectivity characteristic which is shaped to include reduced-response serrations at predetermined desired frequencies.

It is another object of the invention to provide a superregenerative wave-signal translating system including improved means for effecting variations of the regenerative circuit conductance to establish a selectivity characteristic exhibiting reduced-response serrations at particular frequencies.

2

A superregenerative wave-signal translating system, in accordance with the present invention, comprises a regenerative oscillatory circuit having a predetermined oscillatory frequency. The system includes quench means coupled to the regenerative circuit for effecting a major cycle of conductance variation in the regenerative circuit to provide superregenerative amplification of the wave signal applied thereto, the major cycle having a portion representing a conductance change from a positive to a negative value. Additionally, there is provided a signal-generating network so proportioned as to develop a periodic signal component which has a frequency of the same order of magnitude as the major conductance-variation cycle but which is substantially less than one-half the predetermined oscillatory frequency and which occurs in such time relation with respect to the major cycle when applied to the regenerative circuit to effect in at least the aforementioned portion of the major cycle an undulation corresponding to the superposing of a minor cycle of conductance variation on the major cycle. There is also provided coupling means for applying the periodic signal component to the regenerative circuit. Such a system has a substantially uninterrupted frequency-response characteristic with at least one reduced-response serration at a frequency spaced in the frequency spectrum from the oscillatory frequency of the regenerative circuit and related to the occurrence of the minor conductance-variation cycle within the major cycle.

For a better understanding of the present invention, together with other and further objects thereof, reference is had to the following description taken in connection with the accompanying drawings, and its scope will be pointed out in the appended claims.

In the drawings, Fig. 1 is a circuit diagram partially schematic of a complete superregenerative wave-signal receiver embodying the present invention; Figs. 2a, 2b, and 2c are curves utilized in explaining the operation of the receiver of Fig. 1; Fig. 3 represents a superregenerative receiver of the separately quenched type embodying a modified form of the invention; Fig. 4 is a curve indicating the wave form of the quench signal suitable for use in the receiver of Fig. 3; Fig. 5 represents a modified form of signal-generating system suitable for controlling the conductance of the superregenerator of Fig. 3 and Figs. 6a, 6b comprise curves used in explaining the operation when the modification is employed; Fig. 7 is a modified form of self-quenching superregenerative amplifier in accordance with the invention; Fig. 8 comprises curves utilized in explaining the operation of the arrangement of Fig. 7; and Fig. 9 is a further modification of the invention as embodied in a superregenerative amplifier of the self-quenching type.

Referring now more particularly to Fig. 1, the arrangement there represented is a superregenerative wave-signal receiver of the self-quenching type operated in the logarithmic as distinguished from the linear mode. Linear-mode operation is characterized by the fact that the periodically generated oscillations are quenched before attaining saturation-level amplitude, whereas in logarithmic or saturation-level mode operation the quenching action takes place after the oscillations reach saturation-level amplitude. The receiver comprises a regenerative oscillatory circuit including a triode vacuum tube 10 having

75 the usual anode, cathode, and control electrodes. The oscillatory frequency of the regenerative circuit is predominantly determined by a resonant circuit comprising an inductor 11 and condensers 12, 13, 14, and 15. The resonant circuit may include a damping resistor 16 and its resonant frequency may be adjusted through the use of variable inductive or capacitive circuit components. As shown, the inductor 11 is adjustable for tuning purposes. The anode of tube 10 is conductively connected to the junction of inductor 11 and condenser 12. The control electrode is grounded through a condenser 17, thereby effectively being connected to the side of the 15 resonant circuit opposite that to which the anode is connected. The condenser 17 is shunted by a grid-circuit stabilizing resistor 18. The cathode of the tube 10 is connected to ground through a signal-frequency choke coil 19 and is conductively 20 connected to the junction of condensers 12 and 13 to complete the alternating-current paths of a Colpitts type of regenerative oscillatory circuit. The quenching means conventionally included in the regenerative circuit of a self-quenching 25 superregenerative receiver is provided by the condenser 14 and a resistor 20 which couples the condenser 14 to a source of unidirectional potential, indicated as +B. An inductor 21 is connected in shunt relation to the condenser 15 and 30 is included with the resistor 20, the potential source +B, and the inductor 11 in an energizing circuit for the anode of the tube 10. The inductor 21 and condenser 15 provide a signal-generating network for periodically developing 35 and applying to the regenerative circuit a periodic or alternating-current signal component for a purpose to be explained hereinafter. An antenna-ground system 22, including an inductor 23 inductively coupled to the inductor 11 of the 40 frequency-determining circuit, constitutes means for applying a received wave signal to the regenerative circuit for superregenerative amplification thereon.

An inductor 24, inductively coupled with the 45 inductor 11 of the frequency-determining circuit 11-16, is included in the receiver for deriving an output signal from the regenerative circuit. The inductor 24 is coupled to the input circuit of a conventional envelope or averaging detector 50 25 to the output circuit of which is coupled an audio-frequency amplifier 26 of any desired number of stages. A sound-signal reproducing device 27 is coupled to the output circuit of the audio-frequency amplifier 26 to utilize after amplification 55 the modulation components derived by the detector 25.

Neglecting for the moment the signal-generating network provided by the condenser 15 and the inductor 21, the described arrangement comprises a logarithmic-mode superregenerative receiver of the self-quenching type in which the self-quenching network 14, 20 thereof is included in the anode circuit of the regenerator tube 10. In operation, the condenser 14 is charged from 60 the source +B through the resistor 20 and is discharged through the anode-cathode circuit of the tube 10. During the conductive intervals of the tube 10 in which the condenser discharge takes place, the regenerative circuit generates 65 oscillations at a frequency determined by the resonant circuit 11-16. Such oscillations are quenched in the following operating interval in which the tube 10 is nonconductive while the condenser 14 is recharged from the source +B. This provides conventional superregenerative

amplification of a wave signal applied to the regenerative circuit from the antenna system 22, 23. The conductance of the regenerative circuit has positive values during operating intervals in which the tube 10 is nonconductive and the condenser 14 is charging from the potential source +B. On the other hand, the circuit conductance has a negative value during intermediate operating intervals in which the tube 10 is conductive to discharge the condenser 14. The nominal quenching frequency, determined by the charging and discharging time constants of the condenser 14, is selected to have a value which is low relative to the oscillatory frequency of the regenerative circuit but preferably at least twice as high as the highest modulation frequency of the received wave signal. However, as is characteristic of a self-quenching superregenerator, the quenching frequency is not fixed during the reception of an amplitude-modulated signal but rather varies in accordance with the modulation components of the received signal. The variation in quench frequency is manifested in the recurrence rate of the generated oscillations which are supplied through the inductor 24 to the detector 25 wherein the modulation components of the received signal are detected for further amplification in the audio-frequency amplifier 26. Thereafter, the modulation components are applied to the sound-signal reproducing device 27 for utilization in the usual manner. During operation of the receiver, the network 17, 18 stabilizes the quench frequency of the superregenerator.

The foregoing description neglected the function of the signal-generating network 15, 21 and considered only the customary cycles of conductance variations established by the self-quenching network 14, 20. The self-quenching network develops a repeating quench signal of approximately saw-tooth wave form and the resulting cycles of conductance variation are of essentially the same wave form. It may be demonstrated that the selectivity or frequency-response characteristic of the superregenerative receiver, when controlled by such a quench signal, is analogous to that of several cascaded parallel-resonant circuits and has a maximum response to received wave signals corresponding in frequency to the oscillatory frequency as determined by the resonant circuit 11-16. So long as the positive conductance periodically exhibited by the superregenerative circuit is of sufficient magnitude to effect complete suppression of the oscillations generated in one quench cycle, thus to prevent their influencing the oscillations developed in the next succeeding quench cycle, the selectivity curve is smooth. The signal-generating network 15, 21 is included in the regenerative oscillatory circuit to be excited concurrently with the quenching network periodically to develop an alternating-current signal component for modifying the selectivity characteristic. Its action in accomplishing that result may be understood with reference to the idealized conductance-time characteristic of Fig. 2a.

The full-line portions of the curve of Fig. 2a may be considered to represent a major cycle of conductance variation of the regenerative circuit and, except for the specific wave form chosen for the graphical representation, may be deemed to be attributable to the self-quenching network 14, 20. The circuit conductance during the interval t_1-t_2 has a very large positive value; during the interval t_2-t_4 it has zero value; and during the interval t_4-t_5 it has a very large nega-

tive value. This conductance variation may be thought of as repeating periodically to permit the alternate generation and suppression of oscillations in the regenerative circuit to accomplish superregenerative amplification of applied wave signals in the customary manner.

The broken-line curve of Fig. 2a represents what may be considered a minor cycle of conductance variation of the regenerative circuit, said to be minor because it occurs within and is of shorter duration than the first-described major cycle of conductance variation denoted by the full-line curve. This minor cycle, except for its specific wave form, illustrates the conductance variations of the regenerative circuit caused by the periodic signal generated in the network 15, 21. It is clear from Fig. 2a that the minor cycle of conductance variation is superposed on the major cycle and establishes a negative value of conductance within the interval t_2-t_3 and a positive value of conductance within the succeeding interval t_3-t_4 . At the time t_2 when the circuit conductance is entering upon the negative portion of the minor cycle, oscillations are initiated and increase in amplitude until they are damped starting at the time t_3 . Consequently, at the time t_4 when the regenerative circuit has its "principal" maximum sensitivity in the major cycle, that is, just as it enters into the negative-conductance interval of the major cycle, there are two signal components which may influence its response. The first is the received signal applied to the resonant circuit 11-16 from the antenna 22. The second is in the nature of a transient signal resulting from the response of the regenerative circuit due to the minor cycle of conductance variation occurring in the interval t_2-t_4 . The vector addition of these two signal components determines the effective signal amplitude which establishes the initial amplitude of the oscillations initiated in the regenerative circuit at the time t_4 .

At time t_4 , the transient signal has an amplitude relative to the wave signal received by the antenna system 22 in accordance with the net value of conductance integrated over the minor cycle t_2-t_4 . Expressed differently, the amplitude of the transient is determined by the difference between the shaded area A_1 , representing the integrated value of the negative conductance over the interval t_2-t_3 , and the area A_2 , denoting the integrated value of the positive conductance over the interval t_3-t_4 . The amplitude and phase of the transient signal compared with that of the applied amplitude-modulated wave signal govern the effective amplitude of the resultant signal in the regenerative circuit at the time t_4 . Where the two signal components under consideration are in phase, the condition is equivalent to an increased amplitude of the received wave signal and, conversely, a condition in which they are out of phase is analogous to a decrease in amplitude of the received wave signal.

The transient signal has a fixed frequency corresponding to the oscillatory frequency of the regenerative circuit as determined by the resonant circuit 11-16 and it occurs, preferably, in a fixed time relation relative to the major conductance cycle. However, the oscillatory frequency of the transient signal compared with the frequency of the received wave signal is dependent upon the condition of tuning of the circuit 11-16. For that reason, the phase relations of the transient signal and the received wave signal at the interval t_4 of maximum sensitivity of the

regenerative circuit vary as the circuit 11-16 is tuned over its response range. Therefore, the selectivity or frequency-response characteristic of the superregenerator may be of the type represented by the curve of Fig. 2b.

The selectivity curve of Fig. 2b indicates a substantially uninterrupted frequency-response characteristic of the superregenerative receiver with a maximum response at the frequency f_r corresponding to the oscillatory frequency of the regenerative circuit. The characteristic has reduced-response serrations at frequencies f_1 , f_2 , f_3 and f_4 which are spaced from the oscillatory frequency f_r and related to the occurrence of the minor conductance cycle within the major conductance cycle. At each serration, the transient signal resulting from the influence of the minor cycle is 180 degrees out of phase with the received wave signal at the maximum sensitive intervals t_4 of the regenerative circuit. Intermediate the serrations the response has minor peaks at frequencies for which the transient signal and the received wave signal are in phase at intervals of maximum sensitivity. The separation Δf of the two minor peaks closest to the oscillatory frequency f_r is approximately equal to the frequency corresponding to the period t_3-t_4 of the minor conductance cycle. The separation between successive minor peaks on either side of the oscillatory frequency f_r is also substantially equal to Δf , where the selectivity curve is symmetrical about the oscillatory frequency, although a condition of symmetry need not necessarily be obtained as will be explained hereinafter. It should be understood that the minor peaks are present as a result of the effective modulation of the selectivity curve by the minor cycle. Therefore the separation of the minor peaks depends not only on the number of minor cycles present throughout the selectivity bandwidth and the constancy in frequency of the minor cycle but also on the relative slopes of the selectivity curve and the minor cycle. As the relative slopes vary with respect to each other from one minor cycle to the next, the separation will likewise vary. By proper control of the factors just discussed the separations may be equal as indicated in Fig. 2b.

Conductance variations of the type shown by the curves of Fig. 2a may be approximated with the circuit arrangement of Fig. 1. The self-quenching network 14, 20 develops a quench signal of substantially saw-tooth wave form for accomplishing the major cycle of conductance variation. The network 15, 21 develops an alternating-current signal in the form of a damped sinusoid to effect one minor cycle of conductance variation superposed on the major cycle. By suitably selecting the frequency of the network 15, 21 the resultant composite quench signal may have the wave form represented by the curve of Fig. 2c.

In order that the selectivity characteristic may be uniform from one quench cycle to the next, it is preferable that the signal-generating network 15, 21 be synchronized with the self-quenching network 14, 20. This synchronization is inherently realized in the arrangement of Fig. 1 since the network 15, 21 receives a pulse of excitation each time the tube 10 becomes conductive under control of the network 14, 20. It is sometimes advantageous to provide sufficient damping in the network 15, 21 that the transient signal generated therein has a duration not appreciably longer than that of the major cycle of conductance variation. The damping may be provided by the

inherent resistance of the inductor 21 or a separate damping resistor, not shown, may be connected in shunt relation to the inductor 21 to augment its inherent resistance.

In practical embodiments of the described receiver it is desirable to select the resonant frequency of the network 15, 21 to be very much less than the oscillatory frequency of the regenerative circuit to obviate appreciable excitation of that network by the oscillations generated in the regenerative circuit during its major negative-conductance intervals.

The resonant frequency of the network 15, 21 is also significant with regard to the continuity of the response characteristic of the superregenerative receiver in the frequency spectrum. When the resonant frequency has a value of the same order of magnitude as the major conductance cycle, the superregenerator has a continuous or a substantially uninterrupted frequency-response characteristic. The expression "substantially uninterrupted frequency-response characteristic" is used here and in the appended claims to mean a continuous range of response within a continuous frequency band even though the reduced-response serrations previously described may reduce the response to a very low value or to zero at one or more frequencies within that band. To realize an uninterrupted response, the resonant frequency of the network 15, 21 and the frequency of the periodic signal developed thereby to effect the minor conductance cycle may be of the same order of magnitude, that is, may be within a range from one and one-half to ten times the frequency of the major conductance cycle. Resonant frequencies of three to four times the principal quench frequency are useful in many applications of the present invention although it is not necessary to have an integral relation between the quench frequency and the resonant frequency of the network 15, 21.

The parameters of the resonant circuit 15, 21 regulate the depth of the reduced-response serrations because they control the amplitude of the transient signal relative to the wave-signal amplitude, as modified by the frequency-response characteristic of the resonant circuit 11-16 at the sensitive intervals t_4 of Fig. 2a. Where these signals are of approximately equal amplitudes at any of the frequencies f_1 , f_2 , f_3 or f_4 , the serration at such frequency extends to about the abscissa axis in Fig. 2b, indicating substantially zero response. Since the relative amplitudes and phase relations of the two signals may be controlled by appropriately selecting the parameters of the network 15, 21, it is possible to adjust the depth and location of the reduced-response serrations to shape the selectivity characteristic in a desired manner.

In one embodiment of the Fig. 1 arrangement found to have practical utility, the following circuit constants were employed although they are not to be construed as limiting the application of the invention to the use of any particular circuit constants:

Tube 10, half section of a type 12AT7
Resistor 16, 6,800 ohms

Resistor 18, 15,000 ohms

Resistor 20, 10,000 ohms

Condenser 12, 10 micromicrofarads

Condenser 13, 10 micromicrofarads

Condenser 14, 110 micromicrofarads

Condenser 15, 1,200 micromicrofarads

Condenser 17, 3,000 micromicrofarads

- Potential source +B, 250 volts
 Frequency of major conductance variations, 35 kilocycles
 Resonant frequency network 15, 21, 160 kilocycles
 Oscillatory frequency of the regenerative system, 22 megacycles
 Trap frequency separation:
 $(f_3 - f_r)$, 90 kilocycles
 $(f_4 - f_r)$, 230 kilocycles

It will be apparent from the above description of the Fig. 1 arrangement that it is quite convenient to utilize the present invention in a self-quenching superregenerative receiver which includes in its regenerative system a network for developing periodic signals to effect the minor cycles of conductance variation in synchronism with the major cycles of conductance variation. However, the invention is not limited to superregenerative receivers of the self-quenching type but may be utilized equally well in those receivers where the quenching action is under the control of a signal-generating network that is external to or separate from the regenerative system. Such an embodiment is represented in Fig. 3 which in many respects is similar to that of Fig. 1 and corresponding components thereof are designated by similar reference characters. The unit 10' may be any conventional superregenerative amplifier of the externally or separately quenched type including a quench-signal input circuit for receiving a quench signal to effect superregeneration. The quench-signal source 30 of the present arrangement constitutes a signal-generating system including means for developing a first periodic signal component of saw-tooth wave form for effecting the usual major cycles of conductance variation in the superregenerative circuit. Unit 30 includes an additional network for generating a second and sinusoidal signal required to establish the aforementioned minor conductance cycles in the regenerative system. More specifically, the unit 30 comprises a blocking oscillator provided by a triode vacuum tube 31 and a resonant frequency-determining circuit. That resonant circuit comprises an inductor 32 which may be adjustable to facilitate a selective control of the period of the major cycles of conductance variations in amplifier 10'. The resonant circuit further includes condensers 33, 34, 35 and 36 as well as a damping resistor 37. The cathode of the tube 31 is connected to ground through a signal-frequency choke coil 38 and is also connected to the junction of the condensers 33 and 34. Its anode is directly connected to one terminal of the resonant circuit 32-37 and its control electrode is effectively connected to the opposite terminal thereof through a condenser 39. The control electrode is coupled through a stabilizing network, comprising series arm resistors 40 and 41 and a shunt-arm condenser 42, to a source of unidirectional potential indicated as +B. A source of space current +B is connected to the anode electrode of the tube 31 through a decoupling resistor 43 and the inductor 32. An inductor 44 is connected in shunt relation to the condenser 35 to provide a network for developing a sinusoidal signal utilized to effect minor cycles of conductance variation in the superregenerative amplifier 10'.

Neglecting for the moment the function of the network 35, 44, unit 30 is a conventional grid-circuit stabilized blocking oscillator which develops across the condenser 36 in the anode-cathode circuit of the tube 31 a signal potential of saw-tooth wave form occurring at the block-

ing frequency of the oscillator. The periodic pulses of anode-cathode current of the tube 31 excite the resonant circuit 35, 44 to develop a signal of damped sinusoidal wave form. The quenching signal applied by way of a coupling condenser 45 to the quench-signal input circuit of the superregenerative amplifier 10' therefore has a repeating wave form which may be of the type represented by the curve of Fig. 4. The quenching signal includes a component of saw-tooth wave form and a superposed damped sinusoid component. The saw-tooth component considered alone effects the major cycles of conductance variation in the amplifier 10' to provide conventional superregenerative amplification of applied wave signals. The superposed sinusoid component has a frequency higher than, but of the same order of magnitude as, the saw-tooth component and occurs with a predetermined phase relation to the saw-tooth component since the network 35, 44 is excited in a given time relation with each pulse of anode-cathode current of the tube 31 and thus in a given phase relation to the developed saw-tooth component. The sinusoid component effects additional minor cycles of conductance variation in the superregenerative amplifier 10' superposed on each major conductance cycle to impart reduced-response serrations to the selectivity characteristic of the superregenerative amplifier as explained in connection with the curve of Fig. 2b.

It is desirable that the quench-signal output circuit of the blocking oscillator 30 be coupled to the control electrode of the superregenerator vacuum tube included within the amplifier 10' because the circuit of the control electrode is in the nature of a low-current source. This avoids appreciable excitation of the signal-generating network 35, 44 by the oscillations periodically generated within unit 10'. The resonant frequency of the network 35, 44, as well as its damping, determines the number of minor cycles of conductance variation which the signal developed therein is able to superimpose on the major conductance cycles of the superregenerator 10'. The parameters of the network 35, 44 are selected to effect a selectivity characteristic with reduced-response serrations of controlled depth at desired frequencies within the frequency-response range of the superregenerative amplifier 10'.

Fig. 5 represents a signal-generating network which may be substituted for the unit 30 to control the conductance of the superregenerative amplifier 10' in the receiving arrangement of Fig. 3. The generating system of Fig. 5 is essentially a Hartley oscillator including a triode vacuum tube 120 and an associated resonant or frequency-determining circuit 121, 122. One terminal of the resonant circuit is directly grounded and the other is connected to the control electrode of the tube 120 through a grid condenser 123 and a leak resistor 124. The anode of the tube 120 is connected to a source of space current, indicated +B, through an integrating network provided by a condenser 125 and a resistor 126 and the cathode is connected to a tap on the inductor 121. A condenser 127 is the usual bypass for the space-current supply. Signal components developed in the resonant circuit 121, 122 and the integrating network 125, 126 are delivered to an output terminal 129 through a signal-attenuating and phase-shifting network provided for adjusting the relative phase and magnitude of those components. The attenuating and phase-shifting network includes a resistor

11

130 of large value and a small condenser 131. One terminal of the resistor is connected to the high potential side of the resonant circuit 121, 122 through a blocking condenser 132 the other terminal thereof being connected to the condenser 131. The opposite terminal of the condenser 131 is connected to the high potential side of the integrating network 125, 126.

In the operation of the signal-generating system of Fig. 5, sinusoidal oscillations are generated in the resonant circuit 121, 122 and these oscillations vary the potential of the control electrode 120 relative to ground. During intervals when the control electrode has its highest positive potential, pulses of anode-current flow in the anode-cathode circuit of the tube and are integrated by the network 125, 126 thereby to develop a signal of saw-tooth wave form. The attenuating and phase-shifting network 130, 131 permits the sinusoidal and saw-tooth signal components to be added together to provide a composite output signal at the terminal 129. This terminal may be connected with the control-electrode circuit of the vacuum tube included in the superregenerative amplifier 10'. Where such a connection has been established, the conductance of the superregenerative amplifier is varied under the control of the composite signal and preferably follows the patterns of Fig. 6a.

In that figure, curve C represents a major cycle of conductance variation of saw-tooth wave form. The portion of the saw-tooth wave form represented by the curve C indicating the change in conductance from a positive to a negative value is conventionally designated the trace portion thereof whereas the sudden change in conductance from a negative to a positive value, represented at the extreme right-hand portion of the curve C, is designated the retrace portion thereof. The curve C represents the conductance variation which would be established in the superregenerative amplifier 10' if the saw-tooth signal component from the generator of Fig. 5 is alone applied to the superregenerator. However, the saw-tooth component is not delivered by itself but is accompanied by the sinusoidal component developed in the resonant circuit 121, 122. The sinusoidal component has approximately the same frequency as the saw-tooth component and its amplitude and phase relative to the saw-tooth component are so determined by the attenuating and phase-shifting network 130, 131 that the conductance-time characteristic of the superregenerative circuit has the form of curve D. Specifically, the amplitude of the sinusoidal component is small compared with the saw-tooth component, usually being one-quarter, or less, of the amplitude of the saw-tooth component. The phase relations established are preferably such that the slope of the characteristic D in the vicinity of the period of maximum sensitivity (when the conductance is zero in an excursion from a positive to a negative value) is very much less than that of curve C. In other words, the sinusoidal component occurs in such time relation with respect to the major cycle as to effect on at least the trace portion of the saw-tooth wave form an undulation corresponding to a minor cycle of conductance variation in the oscillatory circuit superposed on the major cycle. As a result, the slope of the conductance-time characteristic of the superregenerative circuit in the vicinity of maximum sensitivity is very much less than the corresponding slope when the con-

12

ductance-time characteristic is determined solely by the saw-tooth signal component.

The improvement in selectivity resulting from the use of the signal-generating arrangement of Fig. 5 is apparent from the curves of Fig. 6b, in which the broken-line curve E represents the selectivity on the assumption that the conductance variation is of saw-tooth wave form as indicated by curve C of Fig. 6a. The curve E will be recognized as a parabola plotted in decibels. On the other hand, when the conductance-time characteristic of the superregenerator is in accordance with curve D of Fig. 6a, the selectivity is modified to that represented by the full-line curve F of Fig. 6b. It will be seen that the response of the receiver is a maximum at the oscillatory frequency f_r of the superregenerative receiver and that points of reduced response occur at the frequencies f_1 and f_3 , analogous to the corresponding designations explained in connection with Fig. 2b. It is apparent that the selectivity curve F is sharper within the frequency band f_1-f_3 than is the usual selectivity represented by curve E.

25 One signal-generating network of the type shown in Fig. 5 found to have practical utility utilizes the following:

Tube 120, half section of a type 12AT7
Resonant frequency of circuit 121, 122, 100 kilo-
cycles
Condenser 123, 3,000 micromicrofarads
Condenser 125, 1,400 micromicrofarads
Condenser 127, 40 microfarads
Condenser 131, 100-200 micromicrofarad trim-
mer condensers
Condenser 132, 1,000 micromicrofarads
Resistor 124, 47,000 ohms
Resistor 126, 6,800 ohms
Resistor 130, 150,000 ohms
40 Potential source +B, 50 volts

In the arrangement of Figs. 1, 3 and 5, the network for controlling the major conductance cycles and the network for determining the minor conductance cycles are coupled to the same transconductance-control electrodes of the regenerator vacuum tube included in the regenerative system. If desired, however, these networks may be coupled to different transconductance-control electrodes of the regenerator tube as indicated in the embodiment of the invention shown in Fig. 7. In the latter, the superregenerative amplifier includes a pentagrid type of vacuum tube 50 having anode and cathode electrodes and a series of intermediate control electrodes or grids 51, 52, 53, 54, and 55. The second and fourth grids 52, 54 are connected together while the fifth grid 55 is conductively connected to the cathode. A unidirectional potential source +Sc is coupled to the grids 52 and 54 through a decoupling resistor 56 by-passed by a condenser 57. Circuit arrangements are associated with the cathode, the first grid 51, and the anode of the tube 50 to constitute a self-quenching superregenerative amplifier which is generally similar to the superregenerative amplifier of Fig. 1. These circuits include a frequency-determining circuit comprising an inductor 60, a damping resistor 61, and condensers 62, 63, and 64. The cathode of the tube 50 is conductively connected to the junction of condensers 62 and 63 and is grounded through a signal-frequency choke coil 65. The anode is directly connected to one terminal of the resonant circuit 60-64 and the first grid 51 is coupled

to the other terminal through a condenser 66. Resistors 67 and 68 in conjunction with a condenser 69 constitutes a quench-frequency stabilizing network which couples the first grid 51 to a source of unidirectional potential +B. A source of space current +B is connected to the anode of the tube 50 through a decoupling resistor 70 and the inductor 60.

Signals may be supplied to the resonant circuit of the described superregenerative amplifier from input terminals 71, 72 through an inductor 73 inductively coupled with inductor 60. The input terminals 71, 72 may be connected to any suitable signal source, such as an antenna which intercepts modulated carrier-wave signals for superregenerative amplification. An amplified output signal may be derived from an inductor 74 coupled to the inductor 60 and connected to output terminals 75, 76. Any desired utilizing circuit may be connected with the output terminals 75, 76 to receive the signal output of the regenerative amplifier.

The Fig. 7 arrangement as thus far described is a prior grid-stabilized grid-quenching superregenerative amplifier in which the quenching action is analogous to that of the conventional blocking oscillator. During negative-conductance intervals of the regenerative circuit, oscillations are produced at a frequency determined by the resonant frequency of the circuit 60-64. During the generation of such oscillations, peak rectification of the oscillations in the circuit of the grid 51 establishes a charge in the condenser 66 which builds up and blocks the tube 50. At such time, the regenerative system enters upon its positive-conductance interval which endures until the charge in the blocking condenser 66 is dissipated to permit the tube 50 to be conductive again and to initiate the next succeeding interval of negative conductance. These conductance variations are the major conductance cycles which provide superregenerative action.

The minor conductance variations, desired to be superimposed on such major conductance cycles in order to shape the selectivity characteristic, are under the control of a signal-generating network in the form of a resonant circuit 77, 78 connected to the third grid 53. The resonant frequency of the circuit 77, 78 determines the number of minor conductance cycles which occur within each major conductance cycle and the time of their occurrence is synchronized with the major conductance cycles as represented by the curves of Fig. 8. Of these, curve G represents the oscillations characteristically developed in the self-quenching superregenerative system connected to the anode, cathode and first grid 51 of the tube 50. During oscillation generating intervals, grid current flows in the circuit of the third grid 53 as indicated by the curve H. Such current flow excites the signal-generating network 77, 78 to develop a signal having the damped sinusoidal wave form represented by curve J. This signal is applied to the third grid 53 and varies the transconductance of the tube 50, thereby to produce the minor conductance cycles within the duration of and synchronously with the major conductance cycles.

Although the invention has been described as featuring a single network for generating a periodic signal to accomplish minor conductance cycles of the controlled regenerative system, there may be a plurality of such networks for further shaping the selectivity characteristic. While

multiple signal-generating networks may be employed in superregenerative amplifiers of either the self-quenching or separately quenched type, their application to a grid-blocking grid-stabilized self-quenching amplifier has been shown in Fig. 9. The amplifier there represented includes a triode vacuum tube 80 having a frequency-determining circuit 81-85. The anode and cathode electrodes of the tube 80 are connected with the resonant circuit 81-85 in essentially the same way as described in connection with the embodiment of Fig. 1. The control electrode is coupled to the resonant circuit through condensers 86 and 87 in series and is stabilized by the stabilizing network comprised by resistors 88 and 89, a condenser 90, and a source of unidirectional potential +B. This circuit arrangement constitutes a grid-blocking grid-stabilized superregenerative amplifier of the type which is fully explained in applicant's copending application Serial No. 788,765, filed November 28, 1947, entitled "Self-Quench Superregenerative Receiver," and assigned to the same assignee as the present invention.

Signals applied to input terminals 91 and 92 are supplied to the superregenerative amplifier through the inductive coupling between an inductor 93 and the inductor 81 of the resonant circuit 81-85. Output signals from the amplifier are delivered to output terminals 94, 95 by way of an additional inductor 96 also inductively coupled with the inductor 81 of the resonant circuit 81-85.

Periodic signals of sinusoidal wave form relied upon to introduce minor cycles of conductance variations in order to shape the selectivity characteristic are developed in a network coupled to the control electrode of the tube 80. This network comprises shunt-connected condensers 86, 97, and 98 and series inductors 99, 100, and 101. For convenience, that network may be thought of as including a first resonant circuit 102, a second resonant circuit 103, and a third resonant circuit 104. Each of these resonant circuits develops an alternating signal component of a different frequency higher than, but of the same order of magnitude as, the major conductance cycle established by the grid-blocking condenser 87 and its charging and discharging circuits. The periodic signals generated by such resonant circuits superimpose a plurality of minor cycles of conductance variation on the major conductance cycle established by the grid-blocking network, including the condenser 87. Such minor cycles of conductance variation individually modify the selectivity characteristic by introducing reduced-response serrations of the type represented in Fig. 2b. In discussing the curves of Figs. 2a and 2b, it was pointed out that the minor conductance cycle gives rise to a transient signal and that the phase as well as the amplitude of the transient relative to the received wave signal at the maximum sensitivity period t_s determine the response of the superregenerator. It is apparent that the individual circuits 102, 103, and 104 of the embodiment of Fig. 9 accomplish analogous results. By the superposition theory, it is seen that the cumulative effects of the several circuits 102, 103, and 104 influence the response of the superregenerative circuit and control the locations and depths of the reduced-response serrations.

It has been convenient in describing particular embodiments of the invention to discuss its application to the reception and amplification of amplitude-modulated wave signals but, as under-

stood by those skilled in the art, superregenerative systems of the type under consideration may likewise be employed for the translation of frequency or angular modulated wave signals. Since the instant invention is directed primarily to shaping the selectivity characteristic of a superregenerative stage, it may be advantageously used where the signal to be translated is frequency-modulated or angular-velocity modulated. Further, a superregenerative receiver embodying the invention may operate in the linear as well as in the logarithmic mode.

Superregenerative systems incorporating the present invention have decided advantages over those heretofore known in the art. In particular, they have a selectivity characteristic with reduced-response serrations or trap effects of controllable depth occurring at preselectable frequencies. Furthermore, the serrations in the selectivity characteristic appear in every major quench cycle, thereby avoiding limitations of other known arrangements which possess serrated selectivity characteristics but only after the occurrence of several quench cycles.

While there have been described what are at present considered to be the preferred embodiments of this invention, it will be obvious to those skilled in the art that various changes and modifications may be made therein without departing from the invention, and it is, therefore, aimed to cover all such changes and modifications as fall within the true spirit and scope of the invention.

What is claimed is:

1. A superregenerative wave-signal translating system comprising: a regenerative oscillatory circuit having a predetermined oscillatory frequency; quench means coupled to said circuit for effecting a major cycle of conductance variation in said circuit to provide superregenerative amplification of a wave signal applied to said circuit, said cycle having a portion representing a conductance change from a positive to a negative value; a signal-generating network so proportioned as to develop a periodic signal component which has a frequency within a range of one and one-half to ten times the frequency of said major cycle but which is substantially less than one-half said predetermined oscillatory frequency, and which occurs in such time relation with respect to said major cycle when applied to said regenerative circuit to effect in at least said portion of said cycle an undulation corresponding to the superposing of a minor cycle of conductance variation on said major cycle; and coupling means for applying said periodic signal component to said regenerative circuit, whereby said system has a substantially uninterrupted frequency-response characteristic with at least one reduced-response serration at a frequency spaced in the frequency spectrum from said oscillatory frequency and related to the occurrence of said minor cycle within said major cycle.

2. A superregenerative wave-signal translating system comprising: a regenerative oscillatory circuit having a predetermined oscillatory frequency; quench means coupled to said circuit for periodically effecting a major cycle of conductance variation in said circuit to provide superregenerative amplification of a wave signal applied to said circuit, said cycle having a portion representing a conductance change from a positive to a negative value; a signal-generating network so proportioned as periodically to develop a periodic signal component which has a frequency within the range of two to five times

the frequency of said major cycle but which is substantially less than one-half said predetermined oscillatory frequency, and which occurs in such time relation with respect to said major cycle when applied to said regenerative circuit to effect in at least said portion of said cycle an undulation corresponding to the superposing of a minor cycle of conductance variation on said major cycle; and coupling means for applying said periodic signal component to said regenerative circuit, whereby said system has a substantially uninterrupted frequency-response characteristic with at least one reduced-response serration at a frequency spaced in the frequency spectrum from said oscillatory frequency and related to the occurrence of said minor cycle within said major cycle.

3. A superregenerative wave-signal translating system comprising: a regenerative oscillatory circuit having a predetermined oscillatory frequency; quench means coupled to said circuit for effecting a major cycle of conductance variation in said circuit to provide superregenerative amplification of a wave signal applied to said circuit, said cycle having a portion representing a conductance change from a positive to a negative value; a signal-generating network synchronized with said quench means so proportioned as to develop a periodic signal component which has a frequency within a range of one and one-half to ten times the frequency of said major cycle but which is substantially less than one-half said predetermined oscillatory frequency, and which occurs in such time relation with respect to said major cycle when applied to said regenerative circuit to effect in at least said portion of said cycle an undulation corresponding to the superposing of a minor cycle of conductance variation on said major cycle; and coupling means for applying said periodic signal component to said regenerative circuit, whereby said system has a substantially uninterrupted frequency-response characteristic with at least one reduced-response serration at a frequency spaced in the frequency spectrum from said oscillatory frequency and related to the occurrence of said minor cycle within said major cycle.

4. A superregenerative wave-signal translating system comprising: a regenerative oscillatory circuit having a predetermined oscillatory frequency; quench means coupled to said circuit for effecting a major cycle of conductance variation in said circuit to provide superregenerative amplification of a wave signal applied to said circuit, said cycle having a portion representing a conductance change from a positive to a negative value; a signal-generating network so proportioned as to develop a periodic signal component which has a duration substantially that of said major cycle, and which has a frequency within a range of one and one-half to ten times the frequency of said major cycle but which is substantially less than one-half said predetermined oscillatory frequency, and which occurs in such time relation with respect to said major cycle when applied to said regenerative circuit to effect in at least said portion of said cycle an undulation corresponding to the superposing of a minor cycle of conductance variation on said major cycle; and coupling means for applying said periodic signal component to said regenerative circuit, whereby said system has a substantially uninterrupted frequency-response characteristic with at least one reduced-response serration at a frequency spaced in the frequency

spectrum from said oscillatory frequency and related to the occurrence of said minor cycle within said major cycle.

5. A superregenerative wave-signal translating system comprising: a regenerative oscillatory circuit having a predetermined oscillatory frequency; quench means coupled to said circuit for effecting a major cycle of conductance variation in said circuit to provide superregenerative amplification of a wave signal applied to said circuit, said cycle having a portion representing a conductance change from a positive to a negative value; and a signal-generating network included in said circuit so proportioned as to develop a periodic signal component which has a frequency within a range of one and one-half to ten times the frequency of said major cycle but which is substantially less than one-half said predetermined oscillatory frequency and which occurs in such time relation with respect to said major cycle when applied to said regenerative circuit to effect in at least said portion of said cycle an undulation corresponding to the superposing of a minor cycle of conductance variation on said major cycle, whereby said system has a substantially uninterrupted frequency-response characteristic with at least one reduced-response serration at a frequency spaced in the frequency spectrum from said oscillatory frequency and related to the occurrence of said minor cycle within said major cycle.

6. A superregenerative wave-signal translating system comprising: a regenerative oscillatory circuit having a predetermined oscillatory frequency; quench means coupled to said circuit for effecting a major cycle of conductance variation in said circuit to provide superregenerative amplification of a wave signal applied to said circuit, said cycle having a portion representing a conductance change from a positive to a negative value; and a signal-generating network included in said circuit to be excited concurrently with said quench means so proportioned as to develop a periodic signal component which has a frequency within a range of one and one-half to ten times the frequency of said major cycle but which is substantially less than one-half said predetermined oscillatory frequency and which occurs in such time relation with respect to said major cycle when applied to said regenerative circuit to effect in at least said portion of said cycle an undulation corresponding to the superposing of a minor cycle of conductance variation on said major cycle, whereby said system has a substantially uninterrupted frequency-response characteristic with at least one reduced-response serration at a frequency spaced in the frequency spectrum from said oscillatory frequency and related to the occurrence of said minor cycle within said major cycle.

7. A self-quenching superregenerative wave-signal translating system comprising: a regenerative oscillatory circuit having a predetermined oscillatory frequency; self-quenching means included in said circuit for effecting a major cycle of conductance variation therein to provide superregenerative amplification of a wave signal applied to said circuit, said cycle having a portion representing a conductance change from a positive to a negative value; and a signal-generating network included in said circuit so proportioned as to develop a periodic signal component which has a frequency within a range of one and one-half to ten times the frequency of said major cycle but which is substantially

less than one-half said predetermined oscillatory frequency and which occurs in such time relation with respect to said major cycle when applied to said regenerative circuit to effect in at least said portion of said cycle an undulation corresponding to the superposing of a minor cycle of conductance variation on said major cycle, whereby said system has a substantially uninterrupted frequency-response characteristic with at least one reduced-response serration at a frequency spaced in the frequency spectrum from said oscillatory frequency and related to the occurrence of said minor cycle within said major cycle.

15 8. A superregenerative wave-signal translating system comprising: a regenerative oscillatory circuit having a predetermined oscillatory frequency; quench means coupled to said circuit for effecting a major cycle of conductance variation 20 in said circuit to provide superregenerative amplification of a wave signal applied to said circuit, said cycle having a portion representing a conductance change from a positive to a negative value; a signal-generating network including a 25 resonant circuit so proportioned as to develop an alternating-current signal component which has a frequency within a range of one and one-half to ten times the frequency of said major cycle but which is substantially less than one-half said 30 predetermined oscillatory frequency, and which occurs in such time relation with respect to said major cycle when applied to said regenerative circuit to effect in at least said portion of said cycle an undulation corresponding to the superposing of a minor cycle of conductance variation 35 on said major cycle; and coupling means for applying said alternating signal component to said regenerative circuit, whereby said system has a substantially uninterrupted frequency-response 40 characteristic with at least one reduced-response serration at a frequency spaced in the frequency spectrum from said oscillatory frequency and related to the occurrence of said minor cycle within said major cycle.

45 9. A superregenerative wave-signal translating system comprising: a regenerative oscillatory circuit having a predetermined oscillatory frequency; quench means coupled to said circuit for effecting a major cycle of conductance variation 50 in said circuit to provide superregenerative amplification of a wave signal applied to said circuit, said cycle having a portion representing a conductance change from a positive to a negative value; a signal-generating network so proportioned as to develop a periodic signal component which has a frequency higher than, but within 55 a range of one and one-half to ten times the frequency of said major cycle but which is substantially less than one-half said predetermined oscillatory frequency, and which occurs in such time relation with respect to said major cycle when applied to said regenerative circuit to effect in at least said portion of said cycle an undulation corresponding to the superposing of a minor 60 cycle of conductance variation on said major cycle; and coupling means for applying said periodic signal component to said regenerative circuit, whereby said system has a substantially uninterrupted frequency-response characteristic 65 with at least one reduced-response serration at a frequency spaced in the frequency spectrum from said oscillatory frequency and related to the occurrence of said minor cycle within said major cycle.

70 10. A superregenerative wave-signal translat-

ing system comprising: a regenerative oscillatory circuit having a predetermined oscillatory frequency; and a signal-regenerating system associated with said circuit including means for developing a first periodic signal component for effecting a major cycle of conductance variation in said circuit to provide superregenerative amplification of a wave signal applied to said circuit, said cycle having a portion representing a conductance change from a positive to a negative value and including a network so proportioned as to develop a second periodic signal component which has a frequency within a range of one and one-half to ten times the frequency of said first periodic signal component but substantially less than one-half said predetermined oscillatory frequency, and which occurs in such time relation with respect to said major cycle when applied to said regenerative circuit to effect in at least said portion of said cycle an undulation corresponding to the superposing of a minor cycle of conductance variation on said major cycle; and coupling means for applying said second periodic signal component to said regenerative circuit, whereby said superregenerative system has a substantially uninterrupted frequency-response characteristic with at least one reduced-response serration at a frequency spaced in the frequency spectrum from said oscillatory frequency and related to the occurrence of said minor cycle within said major cycle.

11. A superregenerative wave-signal translating system comprising: a regenerative oscillatory circuit having a predetermined oscillatory frequency; quench means coupled to said circuit for effecting a major cycle of conductance variation in said circuit to provide superregenerative amplification of a wave signal applied to said circuit, said cycle having a portion representing a conductance change from a positive to a negative value; a signal-generating network including a resonant circuit so proportioned as to develop an alternating signal component which has a frequency substantially one and one-half that of said major cycle but which is substantially less than one-half said predetermined oscillatory frequency, and which occurs in such time relation with respect to said major cycle when applied to said regenerative circuit to effect in at least said portion of said cycle an undulation corresponding to the superposing of a minor cycle of conductance variation on said major cycle; and coupling means for applying said alternating signal component to said regenerative circuit, whereby said system has a substantially uninterrupted frequency-response characteristic with at least one reduced-response serration at a frequency spaced in the frequency spectrum from said oscillatory frequency and related to the occurrence of said minor cycle within said major cycle.

12. A superregenerative wave-signal translating system of the separately quenched type comprising: a regenerative oscillatory circuit having a predetermined oscillatory frequency; and a signal-generating system coupled to said circuit including means for developing a first periodic signal component for effecting a major cycle of conductance variation in said circuit to provide superregenerative amplification of a wave signal applied to said circuit, said cycle having a portion representing a conductance change from a positive to a negative value and including a network so proportioned as to develop a second periodic signal component which has a frequency within a range of one and one-half to ten times the fre-

quency of said first periodic signal component but substantially less than one-half said predetermined oscillatory frequency and which occurs in such time relation with respect to said major cycle when applied to said regenerative circuit to effect in at least said portion of said cycle an undulation corresponding to the superposing of a minor cycle of conductance variation on said major cycle, whereby said superregenerative system has a substantially uninterrupted frequency-response characteristic with at least one reduced-response serration at a frequency spaced in the frequency spectrum from said oscillatory frequency and related to the occurrence of said minor cycle within said major cycle.

13. A superregenerative wave-signal translating system comprising: a regenerative oscillatory circuit having a predetermined oscillatory frequency; and a signal-generating system coupled to said circuit including means for developing a first periodic signal component of saw-tooth wave form for effecting a major cycle of conductance variation in said circuit to provide superregenerative amplification of a wave signal applied to said circuit, said cycle having a portion representing a conductance change from a positive to a negative value and including a network so proportioned as to develop a second periodic signal component of sinusoidal wave form which has a frequency within a range of one and one-half to ten times the frequency of said first periodic signal component but substantially less than one-half said predetermined oscillatory frequency and which occurs in such time relation with respect to said major cycle when applied to said regenerative circuit to effect in at least said portion of said cycle an undulation corresponding to the superposing of a minor cycle of conductance variation on said major cycle, whereby said superregenerative system has a substantially uninterrupted frequency-response characteristic with at least one reduced-response serration at a frequency spaced in the frequency spectrum from said oscillatory frequency and related to the occurrence of said minor cycle within said major cycle.

14. A superregenerative wave-signal translating system comprising: a regenerative oscillatory circuit having a predetermined oscillatory frequency and including vacuum-tube means having a plurality of electrodes; quench means coupled to a first pair of said electrodes for effecting a major cycle of conductance variation in said circuit to provide superregenerative amplification of a wave signal applied to said circuit, said cycle having a portion representing a conductance change from a positive to a negative value; and a signal-generating network coupled to a second pair of said electrodes for developing and applying to said circuit a periodic signal component which has a frequency within a range of one and one-half to ten times the frequency of said major cycle and which occurs in such time relation with respect to said major cycle when applied to said regenerative circuit to effect in at least said portion of said cycle an undulation corresponding to the superposing of a minor cycle of conductance variation on said major cycle, whereby said system has a substantially uninterrupted frequency-response characteristic with at least one reduced-response serration at a frequency spaced in the frequency spectrum from said oscillatory frequency and related to the occurrence of said minor cycle within said major cycle.

15. A superregenerative wave-signal translat-

21

ing system comprising: a regenerative oscillatory circuit having a predetermined oscillatory frequency; quench means coupled to said circuit for effecting a major cycle of conductance variation in said circuit to provide superregenerative amplification of a wave signal applied to said circuit, said cycle having a portion representing a conductance change from a positive to a negative value; a signal-generating network so proportioned as to develop a plurality of periodic signal components of different frequencies individually having a frequency within a range of one and one-half to ten times the frequency of said major cycle but which is substantially less than one-half said predetermined oscillatory frequency, and which occurs in such time relation with respect to said major cycle when applied to said regenerative circuit to effect in at least said portion of said cycle an undulation corresponding to the superposing of a minor cycle of conductance variation on said major cycle; and coupling means for applying said periodic signal component to said regenerative circuit, whereby said system has a substantially uninterrupted frequency-response characteristic with at least one reduced-response serration at a frequency spaced in the frequency spectrum from said oscillatory frequency and related to the occurrence of said minor cycle within said major cycle.

16. A superregenerative wave-signal translating system comprising: a regenerative oscillatory circuit including vacuum-tube means and having a predetermined oscillatory frequency; quench means coupled to said vacuum-tube means for effecting a major cycle of conductance variation in said circuit to provide superregenerative amplification of a wave signal applied to said circuit, said cycle having a portion representing a conductance change from a positive to a negative value; and a signal-generating network also coupled to said vacuum-tube means so proportioned as to develop and apply to said circuit a periodic signal component which has a frequency within a range of one and one-half to ten times the frequency of said major cycle but which is substantially less than one-half said predetermined oscillatory frequency and which occurs in such time relation with respect to said major cycle when applied to said regenerative circuit to effect in at least said portion of said cycle an undulation corresponding to the superposing of a minor cycle of conductance variation on said major cycle, whereby said system has a substantially uninterrupted frequency-response characteristic with at least one reduced-response serration at a frequency spaced in the frequency spectrum from said oscillatory frequency and related to the occurrence of said minor cycle within said major cycle.

17. A superregenerative wave-signal translating system comprising: a regenerative oscillatory circuit having a predetermined oscillatory frequency; quench means coupled to said circuit for effecting a major cycle of conductance variation in said circuit to provide superregenerative amplification of a wave signal applied to said circuit, said cycle having a portion representing a conductance change from a positive to a negative value; and a signal-generating network included in said circuit to be shock excited in each quench cycle to develop a periodic signal component which has a frequency within a range of one and one-half to ten times the frequency of said major cycle but which is substantially less than one-half said predetermined oscillatory

22

frequency and which occurs in such time relation with respect to said major cycle when applied to said regenerative circuit to effect in at least said portion of said cycle an undulation corresponding to the superposing of a minor cycle of conductance variation on said major cycle, whereby said system has a substantially uninterrupted frequency-response characteristic with at least one reduced-response serration at a frequency spaced in the frequency spectrum from said oscillatory frequency and related to the occurrence of said minor cycle within said major cycle.

18. A superregenerative wave-signal translating system comprising: a regenerative oscillatory circuit having a predetermined oscillatory frequency; means coupled to said circuit for producing a quench signal for effecting a major cycle of conductance variation of saw-tooth wave form in said circuit to provide superregenerative amplification of a wave signal applied to said circuit; a signal-generating network so proportioned as to develop a sinusoidal signal component having a frequency substantially four times that of said major cycle but which is substantially less than one-half said predetermined oscillatory frequency, and which occurs in such time relation with respect to said major cycle when applied to said regenerative circuit to effect on at least the trace portion of said sawtooth wave form an undulation corresponding to a minor cycle of conductance variation in said circuit superposed on said major cycle and coupling means for applying said sinusoidal signal component to said regenerative circuit, whereby the slope of the conductance-time characteristic of said circuit in the vicinity of the period of maximum sensitivity is substantially less than that attributable to said quench signal alone.

19. A superregenerative wave-signal translating system comprising: a regenerative oscillatory circuit having a predetermined oscillatory frequency; means coupled to said circuit for producing a quench signal for effecting a major cycle of conductance variation of saw-tooth wave form in said circuit to provide superregenerative amplification of a wave signal applied to said circuit; a signal-generating network so proportioned as to develop a sinusoidal signal component having a frequency substantially four times that of said major cycle but which is substantially less than one-half said predetermined oscillatory frequency, and which occurs in such time relation with respect to said major cycle when applied to said regenerative circuit to effect on at least the trace portion of said saw-tooth wave form an undulation corresponding to a minor cycle of conductance variation in said circuit superposed on said major cycle; coupling means for applying said sinusoidal signal component to said circuit; and means for so adjusting the relative phase and magnitude of said quench signal and said sinusoidal component that the slope of the conductance-time characteristic of said circuit in the vicinity of the period of maximum sensitivity is substantially less than that attributable to said quench signal alone.

20. A superregenerative wave-signal translating system comprising: a regenerative oscillatory circuit having a predetermined oscillatory frequency; means coupled to said circuit for producing a quench signal for effecting a major cycle of conductance variation of saw-tooth wave form in said circuit to provide superregenerative

23

amplification of a wave signal applied to said circuit; a signal-generating network for developing a sinusoidal signal component having a frequency substantially four times that of said major cycle, and which occurs in such time relation with respect to said major cycle when applied to said regenerative circuit to effect on at least the trace portion of said saw-tooth wave form an undulation corresponding to a minor cycle of conductance variation in said circuit superposed on said major cycle; coupling means for applying said sinusoidal signal component to said circuit; and means, including a signal-attenuating and phase-shifting network, for applying said quench signal and said sinusoidal component to said regenerative circuit with such relative amplitude and phase that

5

10

15

24

the slope of the conductance-time characteristic of said circuit in the vicinity of the period of maximum sensitivity is substantially less than that attributable to said quench signal alone.
